United States Patent Office.

MARTIN STREETER, OF NEW HAVEN, CONNECTICUT, ASSIGNOR TO HIMSELF
AND ARTELL AUSTIN, OF JERSEY CITY, NEW JERSEY.

Letters Patent No. 79,086, dated June 23, 1868.

IMPROVEMENT IN SHUTTER-OPERATOR.

The Schedule referred to in these Letters Patent and making part of the same.

TO ALL WHOM IT MAY CONCERN:

Be it known that I, MARTIN STREETER, of New Haven, in the county of New Haven, and State of Connecticut, have invented a new and improved Blind-Opener and Fastener; and I do hereby declare that the following is a full, clear, and exact description thereof, which will enable others skilled in the art to make and use the same, reference being had to the accompanying drawings, forming part of this specification.

The figure is a horizontal section of a window-frame and attached shutters, illustrating my invention.

My invention has for its object to furnish an improved device, by means of which window-blinds and shutters may be opened, closed, and secured in place when fully closed, when fully opened, or when opened at any desired angle, which shall be simple in construction, and easily operated; and it consists in the combination of the pivoted lever and guide-rod with the window-sill and blind or shutter, and in securing the blind or shutter, when adjusted in position, by clamping the pivoted lever to the guard-plate by means of a screw-knob or handle.

A represents the side casings of the window-frame, B represents the window-sill, and C represents the blinds or shutters. About the construction of all these parts there is nothing new. D is a lever, which is placed in a recess or notch formed in the window-sill B, and which is pivoted to said sill, as shown in the figure. The pivoted part of the lever D, and the recess in which said lever is placed, are covered and protected by a guard-plate, E, as shown in the drawing. F is a guide-rod, which passes through an eye formed upon the outer end of the lever D, and the ends of which are bent and attached to the blind or shutter C, near its front end and rear edges. When the window-ledge is narrow, the inner end of the lever may pass straight in, and has a screw-handle or knob, G, screwed upon its projecting end. When the window-ledge is wide, it is more convenient to bend the inner end of the lever D upward at right angles, and let it pass out through a curved slot in the guard-plate E. In the case first described, the lever is clamped, securing the blind or shutter in place, by screwing the knob or handle G against the edge of the guard-plate E. In the case last described, the blind or shutter is secured in place by screwing the knob or handle G against the side of the guard-plate E. By this construction the blinds or shutters may be opened, closed, and secured in any desired position, without opening the window, and no hooks or catches are required to secure the blinds either open or shut.

I claim as new, and desire to secure by Letters Patent—

Securing the blind C in any desired position, by means of the screw-handle G, upon the screw-shank of the lever D, acting upon the curved edge of the plate E, as herein shown and described.

The above specification of my invention signed by me, this 25th day of January, 1868.

M. STREETER.
